UNITED STATES PATENT OFFICE.

WILLIAM C. HEEGN, OF CHICAGO, ILLINOIS.

STATION-INDICATOR.

SPECIFICATION forming part of Letters Patent No. 440,406, dated November 11, 1890.

Application filed June 30, 1890. Serial No. 357,249. (No model.)

To all whom it may concern:

Be it known that I, WILLIAM C. HEEGN, a citizen of the United States, residing at Chicago, in the county of Cook and State of Illinois, have invented a new and useful Improvement in Station-Indicators, of which the following is a specification.

My invention relates to improvements in the class of indicators used upon cars for displaying the names of the successive streets or stations as they are approached by the car for the information of passengers; and my object is to provide a device of this character of a comparatively simple and improved construction, which shall be practically automatic and thoroughly effective in its operation.

In the drawings, Figure 1 is a diagrammatic view showing my device applied to a railway-car, the latter being indicated by dotted lines, which illustrate it in broken longitudinal section; Fig. 2, an enlarged broken view, partly in section and partly in elevation, of that part of my improved mechanism which, as herein-after described, is located on the under side of the car; Fig. 3, an enlarged perspective view of a detail showing the preferred construction thereof; Fig. 4, an enlarged view in side elevation of the mechanism contained in the display-case, which latter is indicated in dotted lines; and Fig. 5, a broken section taken on line 5 of Fig. 4, and viewed in the direction of the arrow.

The display-case A should be secured in an overhead location and exposed position in the car, and it has an opening in its face x which may be closed with a pane of glass.

As the operation of my indicator is practically the same whether applied to a street or railway car, I shall for the purposes of brevity and convenience confine its description in connection with the latter, as illustrated in the drawings.

The names of the stations which the car passes are printed in succession upon a web of paper or fabric I, which is fastened at opposite ends upon rollers B B', to be unwound a predetermined extent from one onto the other in each operation of the device to cause the names of stations to be brought successively into the field of view, which is the opening in the front x. The rollers B B' are rigid

upon their journals s s', which latter have their bearings in opposite sides of the case, and between the said rollers and near the front x are two rollers t, over which the web travels, and which cause the latter to extend, with the length thereof being displayed, close to and parallel with the front of the case. At one end of the roller B is a pinion r, loosely mounted upon the journal s, and on the end of the roller adjacent to the pinion is a spring-actuated dog r', which engages the teeth of the pinion and causes the latter in its positive rotation to turn the roller and in its negative rotation to slide over the dog, whereby the roller remains stationary. The journals s s' may, to afford the rollers B B' the necessary resistance against ready turning, be reduced toward the ends, as shown in Fig. 5, to afford shoulders q when friction-springs q' are provided, having perforations through their centers to surround the reduced portions of the journals, and are compressed into position to bear at their centers, around the perforations, against the said shoulders, and at their ends against the adjacent sides of the case.

C is a lever fulcrumed upon a shaft p and having an arm C' on one side of the fulcrum and a segmental toothed edge C² on the opposite side of the fulcrum engaging the teeth of the pinion r. The shaft p is rigid, being secured at one end to the side of the case and at the other in a bracket o, extending upward from the base of the case. A coiled spring D is secured at one end to the shaft p, and at the opposite end to a pin n, extending from the side of the lever. The tendency of the spring D is to turn the lever from the position shown in Fig. 4 in the direction of the arrow, to cause it to strike at its point m against a stop l, which extends from the side of the case across the path of the lever.

On the under side of the car is a hanger E, at the lower end of which is pivoted a bar or lever F, which extends normally vertically downward, and comprises an arm k below the pivot, and a bifurcated part above the pivot affords two diverging cam-faced edges k', preferably segmental, as shown.

G is a lever fulcrumed at one end to a bracket i on the under side of the car and

bearing between its ends against a stiff spring h , confined in a suitable housing h' , also on the under side of the car. On the free end of the lever G is a laterally-extending roller g , 5 which projects between the bifurcated parts of the bar F , and is caused by the action of the spring h , to press against the cam-faces toward the crotch formed thereby and maintain the bar vertical. A cord or other flexible medium f is fastened at one end to the free end of the lever G and at its opposite end to the end of the arm C' of the lever C . It is drawn tightly between its end connections and operates, owing to the action of the 10 spring h , to maintain the lever C in the position shown, with its arm C' against the stop l . The arm F extends downward a distance, which will cause it to clear all usual obstructions along the road—such as tie-bars, planking, or cross-rails—and it may be located to 15 extend in a plane either between or outside the rails of the track. At a desired point in advance of each station an obstruction H is located in the path of the lower end of the 20 arm F .

Any form of obstruction of the proper height will answer, though the one I prefer to employ and show in the drawings comprises a roller e , set crosswise of the track and 25 mounted on journals having bearings in standards e' , sharpened at their lower ends, which permits them to be driven into a tie to afford the necessary stability.

In operation the web I is wound upon the 30 roller B' , the journal s' of which is squared at one end to receive a key by means of which the winding is effected. As the car approaches a station the arm F strikes an 35 obstruction H , which swings it, and causes one of its cam-edges k' (depending upon the direction of movement of the car) to raise the lever G against the resistance of the spring h , thus slackening the cord f , which permits the spring D to turn the lever C until it 40 strikes at the point m against the under side of the stop l . The segmental toothed edge C^2 of the lever C as it is thus turned rotates the pinion r in the negative direction, which, as before described, does not produce rotation 45 of the roller. When the obstruction H is passed, the resilience of the spring h forces the lever G down, which swings the bar F to the vertical position again and draws upon the cord f . The spring h , it will thus be seen, 50 possesses sufficient resilience to overcome the resistance of the spring D , so that the lever C is swung back until its arm C' meets the stop l again, causing the pinion r to turn in the positive direction and rotate the roller B . 55 The roller B as it rotates winds upon itself from the roller B' so much of the web I as will bring into the field of view the text to be displayed. The operation described is repeated each time an obstruction H is passed, 60 and the web I may be provided with the names of stations in proper order for a round trip of the car or with the series of names re-

peated for any desired number of trips, so that the rewinding of the web upon the roller B' , as before described, need only be done at 65 comparatively long intervals. As the circumference of the roller B with the web winding upon it increases with each rotation, the names to be displayed would have to be printed upon the web at distances graduated accordingly if regulating means were not provided to limit, proportionately with such winding, the distance of rotation of the roller B . I provide such regulating means in the form of a bent stiff arm d , as shown, to afford the stop 70 d' , and fastened at one end rigidly to the lever C . The adjustment of the stop device is such that when the roller B is bare of the web the stop will engage the surface of the roller at the same time that the point m on the lever meets the under side of the stop l , and as the web upon the roller increases and 75 enlarges its circumference the stop strikes the roller more and more in advance to gradually lessen the distance of turning of the lever by the spring D , and consequently the negative rotation of the pinion r , so that the return motion of the lever C , which gives positive rotation to the pinion, and thus rotates the roller, as described, is diminished accordingly, and the winding of the web upon the 80 roller B maintained equal, or substantially so. 85

When more than one indicator is placed upon a car, as at each end, or where the car is divided into compartments, they may all 90 be actuated by the same operating mechanism below the car by connecting them with the lever G in the manner described.

What I claim as new, and desire to secure by Letters Patent, is—

1. In combination with a car, a station-indicator, substantially as described, and operating means therefor, consisting of lever mechanism upon the indicator, and mechanism located below the car, connected with the said lever mechanism, and comprising a movable bar F , supported to project normally downward into the plane of suitable obstructions located on the road-bed to be moved from its normal position by contact from either 100 direction with the said obstructions and thereby actuate the said lever mechanism, and a spring bearing against the bar F and resisting movement thereof from its normal position, as set forth.

2. In combination with a car, an indicator, a downwardly-projecting bar F , pivotally mounted below the car, comprising an arm k , extending down into the plane of suitable obstructions located on the road-bed, and an 105 arm affording a cam k' , a spring-actuated lever G , connected with the indicator mechanism and pressing normally against the cam k' , whereby in the movement of the car contact of the arm k with the said obstructions will 115 swing the lever G and actuate the said indicator, substantially as described.

3. In combination with a car, an indicator and actuating mechanism therefor, compris-

ing an inclosing-case A for the indicator mechanism, rollers B and B' mounted in the case, a web I, secured at opposite ends upon the respective rollers to unwind from the roller 5 B' onto the roller B and extending between the rollers across the field of view, a pinion r, adjacent to the roller B, operating when turned in one direction to rotate the said roller and when turned in the other direction 10 to release the roller, a spring-actuated lever C, geared to the pinion and operative when swung in a direction against the resistance of its spring to rotate the pinion in one direction and when returned by the action 15 of its spring to rotate the pinion in the opposite direction, a downwardly-projecting bar F, pivotally mounted below the car, comprising an arm k, extending down into the plane of suitable obstructions located on the road-

bed, and an arm affording a cam k' a spring-actuated lever G, connected with the indicator mechanism to turn the lever C against the resistance of its spring and pressing normally against the cam k', whereby in the movement of the car contact of the arm k with the 20 said obstructions will swing the lever G against the resistance of its spring to permit turning of the lever C by the action of its spring, and release of the arm k from the obstructions will cause the lever G to be returned by its 25 spring and turn the lever C to its initial position, substantially as and for the purpose set forth.
